[57] CLAIM

The ornamental design for an ambulatory slipper or the like, as shown and described.

DESCRIPTION

FIG. 1 is a perspective view of an ambulatory slipper or the like showing my new design;

FIG. 2 is a top plan view;

FIG. 3 is a bottom plan view;

FIG. 4 is a right side elevational view;

FIG. 5 is a front elevational view;

FIG. 6 is a left side elevational view; and,

FIG. 7 is a back elevational view.

The broken line showing of a foot splint and soft anklet in FIG. 1 is for illustrative purposes only and forms no part of the claimed design.
